United States Patent Office

Des. 227,589

Patented July 3, 1973

227,589

VAN RIDING TOY

Cecil Frederick Adicks, Playa Del Rey, Calif., assignor to Kusan, Inc., Nashville, Tenn.

Filed Mar. 13, 1972, Ser. No. 234,464

Term of patent 14 years

Int. Cl. D21—01

U.S. Cl. D34—15 AJ

FIG1

FIG2

FIG3

FIG4

FIG. 1 is a front elevational view of the van riding toy, showing my new design;

FIG. 2 is a side elevational view thereof;

FIG. 3 is a rear elevational view thereof; and

FIG. 4 is a top plan view thereof.

I claim:

The ornamental design for van riding toy, as shown.
